SKYLIGHT CONSTRUCTION

George Henry Lenke, Elmhurst, Ill., assignor of
one-half to Julius J. Ohlis, Oak Park, Ill.

Application January 28, 1937, Serial No. 122,848

6 Claims. (Cl. 108—16)

This invention relates to skylight construction and has for its object to provide a construction which is simple in parts and more efficient in use than those heretofore proposed.

5 With these and other objects in view the invention resides in novel details of construction and combinations of parts as will be described more fully hereinafter and particularly pointed out in the claims.

10 Referring to the accompanying drawing forming a part of this specification and in which like numerals designate like parts in all the views,—

Fig. 1 is a sectional view illustrating the invention and taken transversely of a skylight supporting member;

15 Fig. 2 is a sectional view of the parts shown in Fig. 1 but taken as on the line 2—2 of said figure and looking in the direction of the arrow;

Fig. 3 is a view in perspective of some of the 20 parts shown in Figs. 1 and 2, said parts separated to illustrate the manner of their assembly;

Fig. 4 is a view similar to Fig. 3 illustrating the method of assembling the shoulder bolt to the gutter plate; and

25 Fig. 5 is a view similar to Fig. 1 but showing the application of this invention to a skylight containing double glazing.

First referring to Figs. 1 to 4 there is disclosed a gutter plate generally identified by the numeral 1 and consisting of a main body portion 2 provided on opposite sides with obliquely depending skirts such as 3 and 4, each skirt terminating in an angularly bent or rounded and upturned edge portion such as 5 to form the gutter 6. A bolt 7 is threaded at its upper end to receive thereon a cap nut 8, and near its lower end there is provided a substantially conical portion 9 whose lower edge constitutes a shoulder adapted to rest against the upper surface of the main body portion 2 of the gutter plate, the extreme lower portion of said bolt below said shoulder passing through said plate and receiving a washer 10 positioned against the underside of said gutter plate, the bolt rigidly secured in place by burring its extreme end as clearly indicated in Fig. 1. To prevent rotation of this bolt with reference to the gutter plate the lower end of the bolt is made of square or other polygonal shape as indicated at 11 in Fig. 4 and both the gutter plate and the 30 washer 10 are provided with correspondingly formed apertures such as indicated at 12 for engagement therewith. These bolts 7 are spaced at desired intervals along the length of the gutter plates and preferably are secured thereto at the factory prior to the assemblage of the skylight.

Skylights are mounted on structural framing members which may be of different formations such as angle bars, channel members, I-beams etc. but in Fig. 1 there is shown for convenience an angle bar 15 which is provided, at spaced intervals in the horizontal flange 16 thereof, with a plurality of preformed round apertures such as 17 for a purpose presently to appear, and the body portion 2 of the gutter plate is provided with similar apertures such as 18 adapted to register with the apertures 17 when the parts are assembled.

A strip 19 of asphaltic felt or other suitable cushioning and/or weather proofing or insulating material is interposed between the flange 16 of 15 the angle bar and the main body portion of the gutter plate and this strip of material is also preformed with apertures such as 20 and 21, the former spaced to accommodate therein the washer 10 and burred end of a bolt 7, and the latter 20 apertures 21 positioned to register with the apertures 17 and 18 just described, the width of the strip 19 being substantially equal to the width of the flange 16 of the angle bar, and the width of the main body portion 2 of the gutter plate 25 being such as to receive said strip and said angle bar between its skirt portions as clearly indicated in Fig. 1.

With the members 2, 19 and 16 properly assembled, the apertures 18, 21 and 17 respectively 30 thereof will be in registry for the reception of a drive screw 22 forced therethrough, it being understood that the drive screw will be of relatively hard metal such as steel and provided on its shank portion with a screw thread of relatively 35 great pitch so that when said screw is driven, the threads thereof will bite into the walls of the apertures 18 and 17 and become tightly engaged therewith to hold the parts 2, 19 and 16 in rigid 40 secured. The material of the gutter plate and the angle bar will be softer than the material of the drive screw to permit the threaded engagement as just described, and said drive screw is provided with a rounded relatively flat head presenting a minimum of protuberance above the 45 gutter plate.

From what has been above described it will be seen that the anchor bolt 7 is rigidly secured to the gutter plate, and that the gutter plate is rigidly secured to the angle bar or other structural 50 supporting unit by the drive screws 22, with a strip 19 of asphaltic felt or other insulating material interposed between said plate and said bar. Further, it will be understood that the polygonal fit between the anchor bolt and the gutter plate 55

prevents turning movement of said bolt when the cap nut 8 is applied or removed, and the shoulder portion 9 of said bolt together with the washer 10 makes possible a substantially waterproof joint by virtue of the pressure exerted when burring the end of the bolt over the washer. In other words the burring pressure is great enough to clamp the washer, the main body portion of the gutter plate, and the shoulder of the bolt tightly in surface contact with each other, while at the same time causing a lateral expansion of the metal of the shank 11 of the bolt into tight engagement with the inner surfaces of the polygonal apertures of said washer and said gutter plate.

In the further assemblage of the skylight, and after the gutter plate has been secured to the supporting structural member such as the angle bar 15, there is provided another strip 25 of asphaltic felt or other suitable insulating material having preformed apertures such as 26 adapted to register with and receive therein the anchor bolts. Preferably these apertures are formed of a diameter substantially equal to that of the upper portion of said bolts so that, when the strip 25 is pressed against the upper surface of the gutter plate, the substantially conical shoulder portion 9 of the bolts will tightly fit and close said apertures and thereby form a substantial seal preventing passage of moisture or air. This strip serves as a seat for the skylight glasses and is shown as having a width substantially equal to the width of the main body portion of the gutter plate, but obviously it could be wider if desired.

Next above the strip 25 is positioned a plurality of spacers generally identified by the numeral 27 shown in section in Figs. 1 and 2 and shown in perspective view in Fig. 10. Each spacer is made of rubber or other compressible material which is impervious to water, and is centrally apertured to receive the anchor bolt, and is of a width as seen in Fig. 1 to substantially fill the space between the opposing edges of the glasses 28 and 29 of the skylight, the purpose of the spacers being to prevent said glasses from contacting the anchor bolts yet permitting relative expansion and contraction of the metallic and glass members under changes of temperature, without injury to either. The spacers can be individual units as illustrated or there may be provided a single separator strip of a length sufficient to receive two or more bolts therethrough but it has been found most desirable to provide the individual units, one for each anchor bolt, due to ease of handling as well as minimum of material. The underside of the spacer unit 27 may be provided with a cut away portion indicated at 30 for various purposes such as saving of material, providing a recess to receive therein any upwardly displaced portion of the weatherproof strip 25 occasioned by the conical shoulder of the anchor bolt, to reduce the thickness of the central portion of the unit to permit a more ready expansion of the material of said unit when pressure is applied to secure the glasses 28 and 29 in position, etc.

With the spacers such as 27 applied over the anchor bolts, the glasses 28 and 29 are laid in position as shown to rest upon the strip 25 with the space between their opposed edges occupied by said spacers, and then a third strip 33 of asphaltic felt or other suitable weather-resisting material, having preformed apertures therein, is applied over the bolts on top of the glasses.

75 A sheet metal cap member generally indicated by

the numeral 34, also having preformed apertures therein, is then applied over the bolts and secured under tension by the cap nut 8 against the strip 33 to complete the skylight assemblage. The sheet metal cap is substantially of the form shown in Figs. 1 and 5, having a main body portion with downwardly divergent skirt portions whose lower edges are outturned to provide flanges disposed in a plane substantially parallel to the plane of the main body portion, said flanges adapted to rest 10 upon the uppermost felt strip 33. By this construction a slight springiness or yieldability is permitted when the cap nut 8 is screwed down tightly against the upper surface of the main body portion, thereby rendering possible a tight 15 joint between the flanges and said strip.

In Fig. 5 there is shown double glazing employed in the skylight construction, that is to say there are provided a plurality of panes of glasses disposed in a common plane constituting the upper glazing, as well as a plurality of panes of glasses disposed in another and lower common plane constituting the lower glazing. All of the parts here illustrated above the plane of the lower surfaces of the upper glasses, as well as all of the parts shown below the plane of the lower surfaces of the lower glasses, are substantially the same as those described and shown with reference to Fig. 1 and consequently need no further description. Therefore the only parts requiring 30 specific mention here are those lying between said planes.

The purpose of double glazing is to provide an insulating air space between the panes as well understood, and to make possible the utilization of glass panes of different kinds, qualities and other characteristics producing different resulting effects on the light rays transmitted therethrough. Consequently the upper and lower glazings are subject to different temperatures namely, the former to outside and the latter to inside temperatures the difference between which may be considerable, and therefore provision is made to take care of the air pressure in the space between these glazings. To this end strips 55 and 56 of suitable cushioning and/or weather proofing or insulating material are placed respectively above the lower glazing and beneath the upper glazing, with a wood separator 57 and a spring brass cushion strip or leaf spring 58 interposed between said insulating strips as shown, all of these members provided with apertures to receive the anchor bolt therethrough. As the pressure varies between the upper and lower glazing, the spring strip 58 will yield accordingly, and permit relative movement of one glazing with respect to the other. The members 55, 56, 57 and 58 are each preferably continuous thereby making a perfect closure in the skylight structure, although it is obvious that each may be made of a plurality of substantially lengthwise adjoining units spanning two or more anchor bolts.

It is obvious that those skilled in the art may vary the details of construction as well as the arrangements of parts without departing from the spirit of this invention and therefore I do not wish to be limited to the exact foregoing disclosure except as may be demanded by the claims.

What is claimed is:

1. In skylight construction the combination of a supporting frame member; a gutter plate; an anchor bolt secured to said gutter plate; independent means to secure said gutter plate to said member; glasses mounted on opposite sides

of said bolt; and a yieldable cap mounted on said bolt and holding said glasses under tension.

2. In skylight construction the combination of a supporting frame member; a gutter plate; a separator strip disposed between said plate and said member and substantially coextensive with said member; an anchor bolt secured to said plate; a fastener for independently securing said gutter plate and said strip to said member, said fastener adapted to maintain said plate, said strip, and said member in substantial parallelism; glasses mounted on opposite sides of said bolt; and bolt engaging means for holding said glasses to said plate.

15 3. In skylight construction the combination of a supporting frame member; a gutter plate; an anchor bolt secured to said plate; independent means to secure said gutter plate to said member; upper and lower glazing comprising glasses mounted on opposite sides of said bolt; a substantially flat separator strip fitted over said anchor bolt and coextensive with said member, said strip having a dished central portion and serving as a yieldable means for spacing the upper glazing from the lower glazing; and means 20 cooperating with said bolt to secure the upper

glazing, the lower glazing and said separating means under tension.

4. In skylight construction the combination of a supporting frame member; a gutter plate and means to secure the same to said member; 5 an anchor bolt independently secured to said plate, the securement adapted to lie above the plane of the uppermost surface of said member and spaced from the first named securement; glasses disposed on opposite sides of said bolt; 10 and means enginging said bolt for holding said glasses to said plate.

5. In skylight construction the combination of a supporting frame member; a gutter plate; an anchor bolt secured to said gutter plate; independent 15 means to secure said gutter plate to said member; glazing extending in opposite directions from said bolt; and bolt engaging means for holding said glazing to said plate.

6. In skylight construction the combination of a supporting frame member; a gutter plate; an anchor bolt secured to said gutter plate; independent means to secure said gutter plate to said member; glasses mounted on opposite sides of 20 said bolt; and bolt engaging means for holding 25 said glasses to said plate.

GEORGE HENRY LENKE.
